UNITED STATES PATENT OFFICE

2,348,276

MECHANICAL SIGN APPARATUS

Andrew J. Alford, McComb, Miss.

Application April 28, 1942, Serial No. 440,859

3 Claims. (Cl. 40—35)

This invention relates to new and useful improvements in changeable exhibitors and more particularly to a sign carrier apparatus for either indoor or outdoor use.

The principal object of the present invention is to provide a sign carrying or hanging apparatus which moves in a manner to bring successively different signs into view for observation by the public.

Another important object of the invention is to provide an exhibiting apparatus which is substantially automatic in operation.

These and various other important objects and advantages of the invention will become apparent to the reader of the following description.

In the drawings:

Figure 1 represents a top plan view.

Figure 2 is a side elevational view.

Figure 3 is a fragmentary enlarged vertical sectional view taken substantially on the line 3—3 of Figure 1.

Figure 4 is an enlarged fragmentary detailed sectional view taken substantially on the line 4—4 of Figure 2.

Figure 5 is an enlarged vertical sectional view taken substantially on the line 5—5 of Figure 2 with a portion broken away.

Figure 6 is an enlarged vertical sectional view taken substantially on the line 6—6 of Figure 3.

Figure 7 is an enlarged fragmentary detailed sectional view taken substantially on the line 7—7 of Figure 3.

Figure 8 is a perspective view of the hanger panel.

Figure 9 is a fragmentary side elevational view showing the post equipped with an eye and a cable at its upper end to the end that the apparatus may be suspended.

Referring to the drawings wherein like numerals designate like parts, it can be seen that the apparatus includes a post 5, which may have its lower end disposed into a floor socket 6, or as shown in Figure 9, the post which is therein denoted by reference character 5a may, instead of the floor socket 6, have an eye 7 in its upper end so that it may be suspended by a cable or like member 8.

Reverting now to the form of the invention shown in all views except in Figure 9, it can be seen that a plurality of brackets 9 are secured to the upper portion of the post 5. These brackets are constructed of channelled material and each includes a horizontal arm *a* and an inclined brace member *b*, each arm *a* having a downwardly turned end portion *c*, welded or otherwise secured

to the post 5 while each bracing leg *b* has a downwardly disposed end portion *d* welded or otherwise secured to the post 5.

The brackets 9 support an annular track 10 at the outer end portions of the arms *a* in the manner substantially shown in Figure 3. The arms *a* may be welded or otherwise secured to the track 10 which is of I-shape in cross section.

Above the arms *a* of the brackets 9 is a bushing 11 secured to the post 5 and, in turn, secured to this bushing 11 is a hub 12 from which radiates a plurality of sign supporting arms 13, the outer end portions of these arms 13 having collars 14 and these collars of the several arms 13 are bridged by tie rods 15 which, of course, serve to stabilize and reinforce the supporting arms.

Below the inner ends of the arms 13 is a wheel 16 and bolts 17 extend through this wheel and upwardly through openings in the arms 13. The bolts 17 are equipped with nuts 18 and spacers 19 are provided on the bolts for spacing the wheel 16 from the arms 13.

Numerical 20 denotes a panel having a horizontally disposed flange 21 at its upper end formed with threaded recesses 22, to receive machine screws 23 which are disposed downwardly through slots 24 in one of the arms *a*.

Numerical 25 denotes an electric motor having a clamp band 26 from which projects a bracket plate 27 having a slot 28 therein to receive machine screws 29, which are driven into threaded recesses 30 in the panel 20. Obviously by loosening these screws 29, the motor can be shifted on the panel 20 to the desired position so that a drive roll 31 on the armature shaft 32 of the motor 25 can be brought into the proper frictional engagement with a driven wheel 33, this wheel being located and suitably secured to a vertical shaft 34 which is journaled through bearing members 35 on a bracket 36 which is suitably secured to the panel 20. The shaft 34 extends upwardly through the flange 21 of the panel 20 and through a bearing 37 rising from the flange 21. The upper end of the shaft 34 is provided with a drive roller 38 for frictional drive with the wheel 16.

A plurality of sign units 39 can be secured by clamps 40 to the arms 13 as suggested in Figures 2 and 5.

As can be seen in Figure 3, the motor 25 can be adjusted by the bracket 27 to get the proper friction between the roller 31 and the wheel 33, and the panel 20 can be adjusted by the machine screws 23 to get the proper frictional engagement of the drive roller 38 with the wheel 16.

Casters 41 are carried by the arms 13 and rising annular track 10.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In a rotary sign apparatus, a post, a hub journaled on the post and having horizontal arms radiating therefrom, brackets radiating from and fixed on the post beneath said arms, a circular horizontal track mounted on the brackets concentric with the post, rollers carried by the arms and running on the track, the outer ends of said arms projecting outwardly of the track, and signs suspended from the outer ends of the arms.

2. In a rotary sign apparatus, a post, a hub journaled on the post, and having horizontal arms radiating therefrom, brackets radiating from and fixed on the post beneath said arms, a circular horizontal track mounted on the brackets

concentric with the post, rollers carried by the arms and running on the track, a ring gear secured to the arms and disposed between the inner ends of the arms and the brackets concentric with the post, and driving means for the ring gear mounted on one of the brackets.

3. In a rotary sign apparatus, a post, a hub journaled on the post and having horizontal arms radiating therefrom, brackets radiating from 10 and fixed on the post beneath said arms, a circular horizontal track mounted on the brackets concentric with the post, rollers carried by the arms and running on the track, a ring gear secured to the arms and disposed between the inner ends of the arms and the brackets concentric with the post, and driving means for the ring gear mounted on one of the brackets, said driving means including a vertical panel secured to the brackets and having a vertical shaft journaled thereon, a gear on the upper end of said shaft engaging the ring gear, and a motor mounted on the panel and geared to said shaft.

ANDREW J. ALFORD.
